MARTIN RYERSON, OF HUNTSVILLE, ALABAMA.

Letters Patent No. 68,237, dated August 27, 1867.

IMPROVEMENT IN SWINGLE-TREES.

The Schedule referred to in these Letters Patent and making part of the same.

TO ALL WHOM IT MAY CONCERN:

Be it known that I, MARTIN RYERSON, of Huntsville, in the county of Madison, and State of Alabama, have invented a new and useful Improvement in Swingle-Trees; and I do hereby declare that the following is a full, clear, and exact description thereof, which will enable others skilled in the art to make and use the same, reference being had to the accompanying drawings, forming part of this specification, in which—

Figure 1 is a top view of my improved iron-rod swingle-tree, showing its attachment to a wagon.

Figure 2 is a partial front view.

Similar letters of reference indicate like parts.

This invention relates to an improvement in swingle-trees or double-trees for wagons, and consists in constructing the swingle-tree of iron rods in a barrel-like form, secured on a strong middle disk, and smaller side disks as supports and braces, and united at the ends by welding or fastening a collar in any convenient manner. This construction makes the swingle-tree exceedingly light, strong, and durable, and it may be attached to the wagon by chains in a manner to be more effective in draught on rough roads.

Two or more bars of rod iron, *a a*, are bound together in barrel form upon a strong middle disk, *b*, and at the ends are united and fastened firmly by welding, or in any suitable manner, with hitching-hooks or eyes *c c* at the extremities in the usual way. Between the ends and the middle disk *b* are placed smaller intermediate disks *b' b'*; which serve, with the middle disk *b*, to support the rods *a a* and brace them firmly, so as to give the swingle-tree thus constructed immense strength compared with its weight. Short rods extend from the small disks *b' b'* to the ends of the double-tree. At the back part of the ring *b* is fastened a hook, *d*, for connecting with three chains that are fastened to the axle of a wagon, the middle chain running straight back in the direct central line of draught, and the two outside chains attached to the axle-tree at equal distances on each side of the middle chain, as shown in red lines in fig. 1. By this method of attaching the swingle-tree to the axle-tree of a wagon the draught of the horses is always exerted directly upon the wheel which is overcoming an obstacle in the road, and is equalized or divided upon the two wheels alike when they have equal resistance on the road to their movement. On the lower side of the swingle-tree a pin, *e*, is fastened on the middle ring *b*, for the purpose of connecting with the draught-pole as usual.

Having described my invention, I claim as new, and desire to secure by Letters Patent—

A swingle-tree, constructed of iron rods *a a* in a barrel form, bound together and supported by disks *b* and *b' b'*, and arranged and applied substantially as herein described.

MARTIN RYERSON.
